UNITED STATES PATENT OFFICE.

EDWARD A. POHLMAN, OF NEW YORK, N. Y.

CONICAL WATER-COCK.

SPECIFICATION forming part of Letters Patent No. 645,184, dated March 13, 1900.

Application filed April 14, 1899. Serial No. 713,068. (No model.)

To all whom it may concern:

Be it known that I, EDWARD A. POHLMAN, a citizen of the United States, residing at the city of New York, borough of Manhattan, in the county of New York and State of New York, have invented a new and useful Conical Water-Cock—a combination of a conical-shape metallic core and valve, a tubular hollow stem, a hollow handle, and a longitudinal air-chamber passing through the center of the core or valve and the stem into the shell of the handle—of which the following is a specification.

My invention relates to improvements to water-cocks; and the objects of my improvements are, first, to provide by a longitudinal air-chamber passing through the center of the core or valve the stem to the inside of shell of handle, a water-cock containing an air-cushion which prevents concussion or water-hammering; second, to provide a self-tightening water-cock by a metallic conical shape core or valve having its small end looking downward in waterway adapted to its shape and held firmly in its seat by a spring around the tubular stem and between the superior part of the core or valve and bonnet of cock; third, to provide a durable and lasting water-cock which requires no washers and prevents the swelling and rupture of water-pipes by concussion or water-hammering, and, fourth, to provide a water-cock which overcomes the effects of heat expansion. I attain these objects by the mechanism illustrated in the accompanying drawings, in which—

Figure 1 is the external view of the water-cock. Fig. 2 is a sectional view of the entire cock. Fig. 3 is a sectional view of the barrel or shell of cock. Fig. 4 is a sectional view of the core or valve, stem, and handle; Fig. 5, a spring; Fig. 6, a side view of bonnet, and Fig. 7 a top view of bonnet.

Like letters refer to similar parts throughout the several views.

The core or valve A is of conical shape, its largest end being attached to stem B, its smallest end when attached to and in the waterway C of cock being downward, the core or valve A on one side having an opening D for the passage of water to spigot E when the water is turned on, and when the water is turned off the opening D is firmly pressed

against the blank side of the barrel or shell of cock. Passing through the center of core or valve A is a longitudinal opening or air-chamber F, which extends upward through the tubular stem B into the shell of handle G. The waterway C from just below the attachment of the spigot E is adapted to the form and shape of the core or valve A that the core or valve may set tightly in the waterway C at that point. The spring H when in position is around the tubular stem B between the superior surface of the core or valve A and handle G and held in place by bonnet I, which has an opening J in its center for the passage of the stem B. The spring H exerts a force downward upon the core or valve A and keeps it firmly in its seat in waterway C. The longitudinal air-chamber F above the opening D in core or valve A having no vent forms an air-cushion to overcome the water-pressure in waterway C. Fig. 2 shows a sectional view of the aforesaid parts of the water-cock in position and ready for use.

I am aware that prior to my invention water cocks and faucets have been made having and containing a core or valve, stem, handle, spring, bonnet, and air-chamber. I therefore do not claim such a combination, broadly, but

What I do claim as my invention, and desire to secure by Letters Patent, is—

1. A water-cock containing a conical-shape metallic core or valve A its largest end being attached to a tubular stem B and its smallest end being downward in a waterway C adapted to its form or shape, the core or valve A having longitudinal chamber F through its center, and an opening D on one side for the passage of water to spigot E and firmly held downwardly on the waterway C by the spring H, thereby overcoming the effects of heat expansion and a self-tightening water-cock without the use of washers, substantially as shown and described.

2. A combination of a conical-shape metallic core or valve A having a central longitudinal chamber F and an opening D on its side for the passage of water to spigot; a tubular hollow stem B, a hollow handle G, waterway C cut out and adapted to the shape of core or valve A, and spring H holding and pressing the core or valve A in its seat in water-

way C thereby without the use of washers making a self-tightening water-cock substantially as shown and described.

3. A combination of a conical-shape metallic core or valve which does not leave its seat in waterway C which is corresponding in shape, being firmly held therein by the spring H operating with a downward pressure, having a central longitudinal opening or chamber F an opening on its side D for the passage of water to spigot when water is turned on, and when the water is turned off the opening D is brought in close contact with the blank shell or barrel of cock, thus forming a self-tightening water-cock substantially as shown and described.

4. A combination of a conical-shape metallic core or valve A which does not leave its seat in waterway C, a tubular hollow stem B; a hollow handle G; a central longitudinal air-chamber F forming an air-cushion above opening D to inside of shell of handle G substantially as shown and described, thereby preventing concussion or water-hammering and the effects of heat expansion.

5. A combination of a metallic conical-shape core or valve; tubular hollow stem and handle containing a central longitudinal air-chamber having no vent, extending from bottom of core or valve A to inside of shell of handle; a spring around the tubular hollow stem B between core or valve A and handle G, held in position by a bonnet I attached to water-cock, substantially as shown and described to prevent rupture or fracture of water-pipes by concussion or water-hammering.

6. A combination of a conical-shape core or

valve A with its small end in a waterway C; its largest and upper end being attached to stem B, it having a central longitudinal opening, and an opening on one of its sides D; a tubular hollow stem B; a hollow handle G; a waterway C cutout and adapted to the shape of core or valve A; a central longitudinal air-chamber F extending through core or valve 45 and tubular stem to inside of shell of handle, forming an air-cushion above opening D in core or valve; a spring H around the stem B between core or valve A and handle G, held in position by bonnet I, having a downward 50 pressure upon the core or valve A, and holding it firmly in its seat in the waterway C, substantially as shown and described, forming a water-cock which without the use of washers is self-tightening, prevents concussion or water-hammering and overcomes the effects of expansion and contraction produced by cold or heat.

7. A combination of a waterway C in shape adapted to a conical core or valve A: a conical core or valve A having a central longitudinal opening F, and an opening D on one side of core or valve A for the passage of water when turned on: a hollow tubular stem B: a hollow handle G, thereby forming an air-chamber from the bottom of core or valve A to inside of shell of handle G, thereby to prevent concussion or water-hammering in cock or water-pipes.
